PLUG-IN ELECTRICAL UNIT

Charles E. Cohn, South Orange, N. J.

Application November 28, 1947, Serial No. 788,609

6 Claims. (Cl. 175—366)

1

This invention relates to plug-in electrical devices, and is more particularly concerned with dry disc or metallic rectifiers that may be substituted for vacuum tube rectifiers.

In the prior art, the replacement of a vacuum tube rectifier with a rectifier of the dry disc or metallic type, such as in radio and other electronic instruments, requires very tedious operations, including in many cases drilling for mountings, re-wiring, soldering, etc.

The general object of this invention is the provision of a unit containing a rectifier of the dry disc or metallic type, such as selenium, cuprous oxide, cupric sulphate, etc., which may be substituted precisely for a vacuum tube rectifier in the same manner as if the vacuum tube rectifier were replaced by another vacuum tube rectifier without the need of any tedious operation, re-wiring, extra mountings, soldering, etc.

The replacement of a vacuum tube rectifier with a metallic rectifier is sometimes desirable in various electronic instruments, such as radio receivers, for example, because it permits instant starting. The device of my invention is superior in other ways to the usual vacuum tube rectifiers due to the special features of its construction which make it more durable.

A preferred embodiment of this invention is illustrated in the accompanying drawing, in which:

Fig. 1 is a vertical longitudinal section partially through the embodiment.

Fig. 2 is a cross section along the line 2—2 of Fig. 1.

Fig. 3 is a top plan view of the embodiment partly cut away.

Referring with more particularity to the drawing in which like numerals designate like parts, the embodiment illustrated comprises an inner cylindrical cup 11 of porcelain or other suitable ceramic material coaxially disposed within an outer cylinder 12 of aluminum, copper, steel, or other suitable metal. The cup 11 is used not only to house the internal electrical components, but to insulate them against short circuits and withstand the heat developed by the components.

The diameter of the cylinder 12 is substantially greater than that of the cup 11 so as to provide a space 13 therebetween. The cylinder 12 is also provided with perforations 14 to freely admit circulating air, all of which contribute to the ability of the device to dissipate rapidly heat from the cup 11.

The upper end of the cylinder 12 is bent inwardly to form a flange 15 which extends and is

2

attached to the cup 11. The lower section 16 of cylinder 12 tapers below the bottom of cup 11 and is secured to a base member 17 similar to the base of an ordinary radio tube. The lower end of cup 11 is secured to the cylinder 12 by means of a flanged annular bracket 18 having its vertical section 19 secured by gluing, or otherwise, to the bottom of the cup 11, and its horizontal section 20 secured by soldering, welding, or otherwise, to a horizontal portion 21 of the cylinder 12.

The upper end of the cup 11 is provided with a horizontal plate or disc 22 of any suitable electrical insulating material, such as mica, dielectric plastic, etc. The plate is somewhat resilient, and the rim 23 thereof is serrated to permit it to be held in position against the inner face of the cup by friction and still permit air to circulate around it.

Within the cup 11, there is centrally disposed a rectifier element 24 of any desired dry disc or metallic type, preferably selenium, and of any suitable size and capacity. The rectifier element illustrated is of the half wave type, but a full wave rectifier may be used instead, if desired. The rectifier is supported on legs 25 and 26 secured to the bottom of cup 11. The terminals 27 and 28 of the rectifier element are electrically connected to leads or conductors 29 and 30 which project through apertures 31 and 32 in the base of cup 11.

Additional leads 33, 34, 35, and 36 are also provided through apertures 37, 38, 39, and 40 of the base of the cup for connection to resistors placed within the cup. The leads 33 and 34 are connected to the ends of a resistor 41, and the terminals 35 and 36 are connected to the ends of a resistor 42. The function of one of the resistors, say resistor 41, is to reduce line voltage, while the other resistor acts as a shunt to obtain the proper voltage for a pilot or julot lamp in a radio receiver, for example. Most radio rectifiers, for example, of the vacuum tube type include elements to provide for one or both of these functions. Accordingly, these resistors are an integral part of the device illustrated to render it an exact equivalent of the usual type of vacuum tube rectifier encountered in the radio field.

The resistors 41 and 42 are supported by threading each one through a pair of apertures 43 and 44, respectively, in the disc 22 before attaching them to their respective terminals in the base of the cup 11. The leads 29, 30, 33, 34, 35, and 36 are connected to prong terminals 45, 46, 47, 48, 49, and 50, the latter being secured

to and projecting from the bottom of the base member 17. Additional prong terminals and leads, such as the terminal 51 and lead 52 and corresponding aperture 53, may be provided for any additional element, or elements, desired in the device.

From the above description it may be seen that this invention embraces devices which are as convenient and simple to use as the ordinary vacuum tubes. By the use of proper materials the construction of these devices obviates difficulties heretofore encountered and results in a sturdy and long lasting unit. Rectifiers made in accordance with this invention can readily be substituted for the usual type of vacuum tube rectifier, and is superior thereto in many ways.

I claim:

1. An electrical device comprising as a unit a cup of an electrical insulating material, a heat conducting shell surrounding said cup and being radially spaced therefrom, means for securing said shell to said cup, electrical elements within said cup, said elements comprising a dry disc rectifier and electrical resistors, and electrical conductors connected to said elements and projecting from the bottom of the cup.

2. An electrical device comprising as a unit a cup of an electrical insulating material, a heat conducting shell surrounding said cup and being radially spaced therefrom, means for securing said shell to said cup, electrical elements within said cup, said elements comprising a dry disc rectifier and electrical resistors, a disc at the top of said cup for supporting said resistors, and electrical conductors connected to said elements and projecting from the bottom of the cup.

3. An electrical device comprising as a unit a cup of an electrical insulating material, a heat conducting shell surrounding said cup and being radially spaced therefrom, means for securing said shell to said cup, electrical elements within said cup, said elements comprising a dry disc rectifier and electrical resistors, a disc of an electrical insulating material at the top of said cup, said disc having apertures through which said resistors are threaded and thereby supported, and electrical conductors connected to said elements and projecting from the bottom of the cup.

4. An electrical device comprising as a unit a cup of an electrical insulating material, a heat conducting shell surrounding said cup and being radially spaced therefrom, means for securing

4
said shell to said cup, electrical elements within said cup, said elements comprising a selenium rectifier, a line voltage dropping resistor and a shunt resistor, said resistors extending longitudinally within the cup, a plate at the top of said cup, means for supporting said resistors on said plate, and electrical conductors connected to said elements and projecting from the bottom of the cup.

5. An electrical device comprising as a unit a cup of an electrical insulating material, a heat conducting shell surrounding said cup and being radially spaced therefrom, means for securing said shell to said cup, an electrical element within the cup, a disc at the top of said cup for supporting said element and electrical conductors connected to and projecting from the bottom of the cup, said disc being of an electrical insulating material and having a serrated periphery in frictional engagement with the inner face of said cup.

6. An article of manufacture comprising a cup of an electrical insulating material, a metallic shell surrounding said cup, said shell being radially spaced therefrom, means for securing said shell to said cup, a selenium rectifier and at least one electrical resistor within said cup, a disc of an electrical insulating material at the top of said cup for supporting said resistor, electrical conductors connected to said rectifier and resistor, said conductors projecting from the bottom of the cup, a base member secured to the bottom of said shell, a plurality of electrical prong terminals secured to said base and projecting from the bottom thereof, each of said terminals being secured to one of said conductors.
